OTHER PUBLICATIONS

Bottle by Voss of Norway ASA ("Voss"); date unknown but prior to filing date of present application.

Primary Examiner—Stella M Reid

Assistant Examiner—Keli L Hill

(74) *Attorney, Agent, or Firm*—Banner & Witcoff, Ltd.

(57) **CLAIM**

The ornamental design for a bottle, as shown and described.

DESCRIPTION

FIG. 1 is a front left perspective view of a bottle showing a first embodiment of our new design;

FIG. 2 is a front view thereof;

FIG. 3 is a right side view thereof;

FIG. 4 is a rear view thereof;

FIG. 5 is a left side view thereof;

FIG. 6 is a top view thereof

FIG. 7 is a front left perspective view of a bottle showing a second embodiment of our new design;

FIG. 8 is a front view thereof;

FIG. 9 is a right side view thereof;

FIG. 10 is a rear view thereof;

FIG. 11 is a left side view thereof; and,

FIG. 12 is a top view thereof.

The broken lines immediately adjacent the shaded areas in FIGS. 7-12 represent the bounds of the claimed design while all other broken lines are directed to environment and are for illustrative purposes only; the broken lines form no part of the claimed design.

1 Claim, 12 Drawing Sheets
